UNITED STATES PATENT OFFICE.

MARTIN J. DONER, OF CHICAGO, ILLINOIS, ASSIGNOR, BY MESNE ASSIGNMENTS, OF ONE-HALF TO C. F. DYNES, OF CHICAGO, ILLINOIS.

STEP-BY-STEP MECHANISM.

1,110,751.

Specification of Letters Patent. Patented Sept. 15, 1914.

Original application filed November 2, 1908, Serial No. 460,461. Divided and this application filed January 15, 1912, Serial No. 671,264. Renewed February 13, 1914. Serial No. 818,608.

To all whom it may concern:

Be it known that I, MARTIN J. DONER, a citizen of the United States, residing in the city of Chicago, county of Cook, and State of Illinois, have invented certain new and useful Improvements in Step-by-Step Mechanism, of which the following is a specification.

This application is a divisional application of an original application filed November 2nd, 1908, by me on automatic signs, Serial No. 460,461 which has matured into Patent No. 1,019,770.

This invention relates to improvements in step by step mechanism and has for its salient object to provide a construction in which an actuated member is moved a given number of steps in one direction, the mechanism then automatically reversed and the actuated member driven a number of steps in the opposite direction to provide a construction of the above character in which the actuated member may take the form of a rack bar having oppositely disposed teeth coöperating with a double reversing pawl automatically operated by an electric motor or other suitable source of power; to provide a construction which is positive and reliable in its operation and yet simple and economical in construction; to provide a construction which has a wide range of uses and can readily be adapted to any form of mechanism to be driven; and in general to provide a simple and improved construction of the character referred to.

The invention consists in the matters hereinafter described and more particularly pointed out in the appended claims.

In the present instance, my improved step by step mechanism is shown as used in connection with an automatic sign, although it is not in anywise limited to such use.

In the drawings Figure 1 shows a side elevation of a sign with which the step by step mechanism is in the present instance used, the slats of the sign being shown in closed position. Fig. 2 is a fragmentary perspective view, the step by step mechanism being shown in perspective; Fig. 3 is an enlarged vertical sectional view on the lines 3—3 of Fig. 1; Fig. 4 is a fragmentary horizontal sectional view of the sign; Fig. 5 is a fragmentary vertical sectional view, the step by step mechanism is shown in side elevation; Fig.

6 is a fragmentary detailed view of the reversing pawl and actuated rack bar.

In the drawings 1 designates as a whole a hollow sheet metal casing comprising vertical end members 2, horizontally extending side frame members 3 and 4 respectively, and enlarged corner portions 5 projecting over the ends of the frame as shown. The inner faces of the horizontally extending members 3 and 4 are closed by means of plates 6 and 7 respectively which serve as base supports for the operating mechanism hereinafter described. The ends of the upper member 6 extend into the enlarged corner portions 5 forming the floor of the latter as shown more clearly in Fig. 2.

The upper and lower supporting strips 6 and 7 are mounted upon the edges of a board or board-like support 10, the side faces of which constitute the sign boards as will hereinafter appear. As a preferred construction the channel irons 11 are secured to each edge of the board 10 and the base supports secured to the channel iron by bolts 11' as indicated clearly in Fig. 3.

At each side of this board 10 is detachably mounted a series of rotatable slats 9, likewise adapted to receive advertisements on their faces. In order that each set of slats may be removed independently of the other, the several members of each row have their trunnions engaged with supporting bars 12, 12' and these supporting bars are detachably secured to the respective plate members 6 and 7 by bolts as indicated at 13. The ends of the supporting members 12, 12' are connected by means of bars 14 (see Fig. 5), so that each set of slats and supports are removable in the form of a rectangular frame. The upper trunnions of the slats extend through and are journaled in the supporting plate 12 as shown clearly in Fig. 3. Each trunnion is provided with a pinion 14, non-rotatably fixed thereon, and confined in position by an end cap 15. The upper supporting member 6 is slotted from each trunnion laterally downward so that the set of slats may be disengaged therefrom. The trunnions at the lower ends of the slats are seated in bearing recesses 16 forming step bearings.

The sets of slats are moved step by step, so as to perform exactly one-half revolution and back, each half revolution being accom-

plished in four steps. To impart this movement to the slats, mechanism is provided as follows: Upon the base support 6 is mounted to reciprocate in any suitable guides, a duplex rack-bar 20, provided at its laterally outer edges with rack-teeth which engage with the respective series of pinions of the slats. With one end of the rack-bar is connected a ratchet block 21 provided with two sets of oppositely disposed ratchet teeth, as 22 and 22'; each series of teeth comprising four corresponding to the several steps of movement in each direction. A short distance beyond the outermost teeth of each series is formed a step shoulder 23 which cooperates with a reversing pawl, as herein-after described. Between the respective sets of ratchet teeth a groove 24 is provided in the face of the block, which groove is adapted to receive and guide a downturned end of head 26 of an actuating pitman 25. The pitman 25 is at its opposite end connected with a wrist-pin 29 upon a gear 30 forming one member of a train of gears actuated in the present instance by an electric motor 27. The driving train referred to comprises a worm-gear 31 mounted directly upon the shaft of the motor armature, an intermediate worm-gear 31', a pinion 32 fast with the worm-gear, and the gear 30 hereinbefore referred to, which connects with the pitman.

Upon the head of the pitman is mounted a reversing pawl, designated as a whole 33. This pawl, is a bent member provided at each end with pawl-hooks, as 34, 34', and has a slot-and-pin connection with the pitman head, being provided with a centrally located longitudinally extending slot 35, engaged with a pin 36 carried by the upper part of the head of the pitman. Within the slot 35 is arranged a bow-spring 37 which projects into the central portion of the slot in such manner as to tend to hold the supporting pin 36 in whichever end of the slot it happens to rest until the pawl is shifted positively by engaging with one end or the other against the corresponding one of the stop shoulders 23 hereinbefore referred to. In order to lessen the friction and mechanical power required to actuate the rack-bar, I prefer to mount the latter to roll back and forth upon anti-friction bearings, as indicated at 39. Inasmuch as the reversing pawl is symmetrical in construction, and the slot 35 thereof centrally located, it will be obvious that whenever the pin 36 is in one end of the slot, the opposite end of the pawl will overweight the other and descend by gravity into engagement with the corresponding set of ratchet teeth. Accordingly the pawl will step the rack-bar in one direction, four steps, but upon commencement of the fifth step the then lower end of the 35 pawl will engage the corresponding stop

shoulder, shift the pawl into its reverse position, whereupon the succeeding revolutions will step the rack-bar in the opposite direction four steps. In order to confine the pitman member in proper engagement with the slot in which it slides, the latter is desirably made of inverted T-shape in cross section and a guide pin 38 inserted through the engaging end of the pitman head and arranged to engage the undercut portions of the slot. 75

Upon the outer faces of each side of the fixed division board 10 are painted or otherwise placed any suitable signs which will be fully displayed when the slats are standing with their edges at right angles to the plane of said surfaces and the observer is approximately opposite either side of the sign. When the slats are oscillated into various angles with relation to the stationary signboard and the observer is approaching, *i. e.*, stands at an angle approximately coincident to the oblique angles of the slats, he can also see the stationary sign. 85

The invention is not limited to the details of construction shown, except as set forth in the appended claims. 90

I claim as my invention:

1. A step-by-step mechanism comprising a ratchet member provided with two sets of oppositely disposed ratchet teeth and an intervening guide portion, a reciprocatory pawl actuating member operatively mounted adjacent to said ratchet member and having one end arranged to engage the guide portion of the latter, a double ended gravity pawl member having bodily movable connection with said pawl actuating member, the ends of said pawl member moving in unison, stops upon said ratchet member arranged to engage said double ended pawl at the end of a predetermined number of movements of the ratchet member in each direction to effect the shifting of the pawl actuating member on its movable connection whereby said connection is shifted from one side to the other of the center of gravity of the pawl and said pawl thereby adapted to alternately operatively engage with said series of ratchet teeth. 100

2. A step-by-step mechanism comprising a ratchet block, having ratchet teeth and provided with a longitudinally extending guide way, a pitman traveling in said guide way, means for actuating said pitman, a pawl member adapted to engage the teeth of said ratchet member, and means carried by said pawl member for yieldably holding the latter in a given position during a predetermined movement in the travel of said pitman. 115

3. A step-by-step mechanism comprising a ratchet block, having two series of oppositely disposed ratchet teeth and provided with a longitudinal extending guide-way, a pitman having a down-turned end engaging 130

said guide-way, a pawl member mounted on said pitman and having oppositely disposed pawls for engaging said teeth, a spring member for holding said double ended pawl in a given position during a predetermined travel of the pitman, and means for reversing the position of said pawl member against the action of said spring.

4. A step-by-step mechanism comprising a ratchet block having two oppositely disposed sets of ratchet teeth, a pitman member and means for driving same, a gravity pawl structure having teeth at its ends for co-operating with the respective ratchet teeth sets, said gravity pawl structure having longitudinally shiftable pivot connection with said pitman to either side of its center of gravity whereby the heavier end of said pawl will coöperate with the corresponding set of ratchet teeth to shift said ratchet member, and a stop at each end of said ratchet member for effecting shifting of said pivoted connection at the end of a predetermined number of shiftings of said ratchet member by said pawl structure.

5. A step-by-step mechanism comprising a ratchet block having two oppositely disposed sets of ratchet teeth, a pitman member and means for driving same, a gravity pawl structure having teeth at its ends for co-operating with the respective ratchet teeth sets, said gravity pawl structure having lon-

gitudinally shiftable pivot connection with said pitman to either side of its center of gravity whereby the heavier end of said pawl will coöperate with the corresponding set of ratchet teeth to shift said ratchet member, a stop at each end of said ratchet member for effecting shifting of said pivoted connection at the end of a predetermined number of shiftings of said ratchet member by said pawl structure, and means for yieldingly locking the pivot connection after shifting thereof.

6. A step-by-step mechanism comprising a ratchet member having two sets of ratchet teeth, a pitman member adjacent said ratchet member, a pawl beam spanning between said ratchet teeth sets and having pawl teeth at its ends for coöperating with said sets, said pawl beam having a longitudinal slot extending to either side of its center of gravity, a pivot pin extending from said pitman into said slot, a spring within said slot for yieldingly locking said pawl beam when said pin is at the ends of said slot, and stops on said ratchet member for coöperating with said pawl beam to effect shifting thereof on said pivot member.
